ELECTRIC BOILER

Arnold A. Smith, Three Rivers, Quebec, Canada,
assignor to International Paper Company, New
York, N. Y., a corporation of New York

Application September 24, 1945, Serial No. 618,101

4 Claims.

(Cl. 219—40)

1

It is an object of this invention to provide a control system for electric boilers of the conduction type, which is highly adjustable without being subject to "hunting."

It is a further object of this invention to provide a system of control which operates regardless of changes in electrode condition or scale formation, and at all times within safe limits of water level and current densities.

It is a further object of this invention to provide a control system wherein water density is held at, or near, the maximum permissible, resulting in minimum blow-down with consequent minimum losses.

The above and other objects will be made clear from the following detailed description taken in connection with the annexed drawing which represents, schematically, a particular application of the improved boiler control system.

The fundamental principle of an electric conduction boiler is extraordinarily simple. A boiler drum is provided in which is mounted an electrode. The electrode is partially submerged and is surrounded by a metal shell, also partially submerged. The shell is grounded and current flows from the electrode to the shell, thence to the ground, passing through the water, which is in contact with both the electrode and the shell. The water offers substantial resistance to the passage of the current, and the current encountering this resistance, generates sufficient heat to boil the water. For all practical purposes, the voltage applied is a constant. The amount of current drawn by the system varies, therefore, inversely with the resistance; and since the heating effect is the product of resistance, times the square of the current, the total power input varies inversely as the resistance. The resistance of boiler water depends on the temperature and pressure, and more particularly upon the quantity and nature of the solids in solution in the water. Over any reasonable period of time, however, these factors may be considered constant; and with these factors constant, resistance is inversely proportional to the depth of immersion of the electrode. Since power input varies inversely with resistance, and resistance in turn varies inversely with depth of immersion, power input is a direct function of the depth of immersion.

Given any form of control over the rate of addition of feed water to a boiler chamber as above described, it is possible to meet fluctuations in demand for steam from the boiler by adjusting the depth of immersion of the electrode. It is not, however, sufficient merely to be able to make

an adjustment. At 180 pounds gauge pressure, approximately 8 cubic feet of steam are required per minute in order to supply a demand of 1 boiler horsepower. If such a demand were not met for a period of one minute, the pressure would drop to 150 pounds. It is, therefore, absolutely essential that the response of the control system to a change in the demand be as prompt, and as positive, as possible. The present invention assures 10 promptness of response by constantly conditioning the water to be supplied to a boiler chamber, so that water entering the chamber will always be at a temperature closely approximating (within 10%) the temperature of the water already in the boiler. This system is described hereinafter, with reference to a three phase, three body, installation, as being the type of installation ordinarily most difficult to control. The principles are, however, equally applicable to a three phase, 20 single body installation, or to any other combination.

In the drawings, there are shown three boiler chambers 10, 20 and 30, in each of which is mounted an electrode, respectively designated 12, 22 and 32. Surrounding each electrode is an electrically grounded shell, respectively designated 14, 24 and 34. A surge tank 50 is provided, which has a pressure equalizing connection 52' with each of the boiler chambers 10, 20 and 30, through 30 parallel steam lines, respectively designated 16, 26 and 36. The lines 16, 26 and 36 are steam delivery lines feeding a joint delivery line 84. At the bottom of the surge tank 50 is a conventional blow-down valve 52 and a water outlet 54 connecting with a pump 56. The pump 56 delivers to a water line 58 which is connected with the boiler chambers 10, 20 and 30, by means of parallel connections, respectively designated 18, 28 and 38. Water constantly leaves the boiler chambers 10, 20 and 30 through connections, respectively designated 11, 21 and 31, and, impelled by pumps 13, 23 and 33, is delivered to a line 60 by means of parallel connections 15, 25 and 35. The line 60 delivers water to the surge tank 50. The activity of pumps 13, 23 and 33 and of the pump 56, is such, normally, as to provide a rate of circulation of water through the boiler chambers 10, 20 and 30 equal to approximately five times the normal rate of steam delivery (in weight per unit of time) from each of the boiler chambers.

Make up feed water is delivered to the surge tank 50 through a line 62. The rate of delivery is controlled by a valve 64, which is automatically operated, as will be set forth hereinafter.

Each of the boiler chambers 10, 20 and 30 has

connected therewith an automatic level control, designated respectively as 17, 27 and 37. A main control 80 is connected by a sensing line 82 to the discharge line 84, which receives steam delivered from the three boiler chambers 10, 20 and 30. Control impulses from the regulator 80 are delivered to the level controls 17, 27 and 37 through control lines 17', 27' and 37', respectively. The level control 17 is connected by a line 19 to a valve 19' in the line 15, and by a line 17'' to a valve 19'' in the line 18. The control 27 is connected by a line 29 to a valve 29' in the line 25, and by a line 27'' to a valve 29'' in the line 28. The level control 37 is connected by a line 39 to a valve 39' in the line 35, and by a line 37'' to a valve 39'' in the line 38.

The level of water in the boiler chamber 10 may be adjusted upward by opening the valve 19'' and closing the valve 19', and may be lowered by the reverse adjustment of these valves. So long as pressure in the line 84 remains substantially constant, the level control 17 operates the valves 19' and 19'' to maintain substantially a constant level of water within boiler chamber 10. The level control 27 operates in precisely the same way on valves 29'' and 29' to control the water level in the boiler chamber 20, while the control 37 and the valves 39'' and 39' operate in the same manner as to boiler chamber 30.

When the steam demand increases, there will be a drop in the pressure in the delivery line 84, which drop will affect the controller 80. The controller 80, through lines 17', 27' and 37', will override the normal control of the controllers 17, 27 and 37, causing these to close valves 19', 29' and 39', while opening valves 19'', 29'' and 39''. The circulation system, at this point, operates to fill the boiler chambers 10, 20 and 30, drawing upon water in the surge tank 50. When a level is reached in the boiler chambers 10, 20 and 30, which results in increasing the steam delivery rate to a point at which the desired pressure is attained in the line 84, the effect of the controller 80 is eliminated and the units 17, 27 and 37 resume control, maintaining the level in drums 10, 20 and 30 at the new point.

When there is a sudden drop in the steam demand, there will be a rise in pressure in the line 84. This pressure increase affects the overriding control 80, which in turn operates the units 17, 27 and 37, causing these to open the valves 19', 29' and 39', and to close the valves 19'', 29'', and 39''. This setting withdraws water from the boiler chambers 10, 20 and 30, and delivers the water to the surge tank 50.

The water delivery valve 64 in the feed water line 62 is under the control of a unit 66 through a line 68. The control 66 responds to the level in the surge tank 50. The normal operation of the surge tank 50 calls for the level in said tank to be low during a period of high demand on the line 84, and to be high during a period of low demand. At all times, pressure in surge tank 50 is the same as the pressure in line 84 and in the boiler chambers 10, 20 and 30, and there is a constant circulation of water through the surge tank 50.

Even in a system in which the steam is condensed and returned to the boiler, there are losses which must be made up by additions of fresh water. These losses occur on the steam side, to a greater extent than on the water side. Accordingly, there is a constant tendency to increase the percentage of chemicals dissolved in the water. These dissolved chemicals sharply affect the electrolytic character of the water and may

bring about a current density sufficiently great to cause dissociation with constant gassing. To guard against this condition, a bleeder valve 70 is inserted in the circulation line 60. The valve 70 is operated by a conductivity controller 72 through a line 74. When the specific conductivity of the water attains a predetermined value, the controller 72 opens the valve 70 and bleeds water out of the system until the addition of feed water through the line 62 brings about sufficient dilution to lower the specific conductivity. The operation of the controller 72 and the valve 70, due to the high rate of circulation, is sufficiently prompt to avoid excessive bleeding, and the avoidance of such excess produces great economies over any substantial period of time.

All of the controllers mentioned herein are of standard types and may be bought from a number of sources, such, for example, as the Bailey Meter Company, Foxboro Company, and The Mason Regulator Company. For this reason, the mechanical details of the several controllers have been omitted and the system has, generally been illustrated schematically.

The provision of the surge tank 50 brings about a number of advantages. With the high rate of circulation (five times average demand) and the controlled addition of feed water, incoming feed water has less than a 10 percent effect on the

temperature of water going to the boiler chambers. In addition, the mineral content of the incoming feed water, so far as such content will precipitate under heat, precipitates in the surge tank 50 and collects at the bottom where it may be removed by an ordinary blow-down, using valve 52.

The pumping system which handles water at a rate approximating five times the normal steam demand, is not, as it might seem, an extravagant consumer of power, since most of the time the pumps operate against only a relatively low gravity head and never operate against full steam pressure. This high rate of circulation, however, makes it possible to bring about a rapid adjustment of level in the boiler chambers and thus to provide extremely prompt response to a change in steam demand.

During any period of steady steam demand, the controllers 17, 27 and 37 operate to maintain the requisite level, whether high or low, suitable to meeting such demand. The controller 80 operates only when the static pressure in line 84 exceeds or drops below a predetermined point. There is provided, therefore, individual control of the several boiler chambers, operative during any prolonged level of demand,

such individual control, however, being overridden by the universal control 80 whenever abnormal fluctuations of demand occur.

I claim:

1. In a boiler, a boiler chamber, at least one electrode positioned therein and adapted to be partially submerged in water, an electrically grounded baffle surrounding and spaced from said electrode, a separate surge tank, a pressure equalizing connection between said boiler chamber and said surge tank, a first pump for positively pumping water from said boiler into said surge tank, a second pump for positively pumping water from said surge tank into said boiler, said first and second pumps being capable of handling water at a rate in weight per unit of time greater than the maximum rate of steam delivery from said boiler chamber, and means responsive to steam demand for controlling the relative outputs of said first and second pumps to raise or lower the depth of submersion of said electrode.

2. In a boiler, a boiler chamber, at least one electrode positioned therein and adapted to be partially submerged in water, an electrically grounded baffle surrounding and spaced from said electrode, a separate surge tank, a pressure equalizing connection between said boiler chamber and said surge tank, a first pump for positively pumping water from said boiler into said surge tank, a second pump for positively pumping water from said surge tank into said boiler, said first and second pumps being capable of handling water at a rate in weight per unit of time greater than the maximum rate of steam delivery from said boiler chamber, means responsive to steam demand for controlling the relative outputs of said first and second pumps to raise or lower the depth of submersion of said electrode, and means responsive to a range of water level variations within said surge tank for controlling the supplying of make-up feed water thereto.

3. In a boiler, a boiler chamber, at least one electrode positioned therein and adapted to be partially submerged in water, an electrically grounded baffle surrounding and spaced from said electrode, a separate surge tank, a pressure equalizing connection between said boiler chamber and said surge tank, a first pump for positively pumping water from said boiler into said surge tank, a second pump for positively pumping water from said surge tank into said boiler, said first and second pumps being capable of handling water at a rate in weight per unit of time greater than the maximum rate of steam delivery from said boiler chamber, means responsive to steam demand for controlling the relative outputs of said first and second pumps to raise or lower the depth of submersion of said electrode, means responsive to a range of water level variations within said surge tank for controlling the supplying of make-up feed water thereto, and means responsive to the specific conductivity of the water leaving said chamber for bleeding water from the system to restore dilution to a predetermined value.

4. In a boiler system, a plurality of boiler chambers having a common delivery line, an electrode in each of said chambers adapted to be partially submerged in water, an electrically grounded baffle surrounding and spaced from said electrode, a single surge tank separated from said boiler chamber, a series of parallel connected pressure equalizing connections between said surge tank and each of said boiler chambers, a pump associated with each of said boiler chambers for withdrawing water therefrom and pumping the same into said surge tank, a series of parallel connected pipes connecting said pumps with said surge tank, a pump associated with said surge tank for pumping water therefrom into each of said boiler chambers, a series of parallel connected pipes connecting said pump with each of said boiler chambers, the said pumps together maintaining water circulation at a rate in weight per unit of time greater than the rate of steam delivery from said boiler chambers, means responsive to steam demand for controlling the relative flow of water through the several branches of all of said parallel connected pipes to individually raise or lower in each of said boiler chambers the depth of submersion of said electrodes, and means responsive to a range of water level variations within said surge tank for effecting the supplying of make-up feed water thereto.
